HUBERT C. MORRIS, OF ALBANY, OREGON

IRONING BOARD

Application filed May 12, 1928. Serial No. 277,275.

The primary purpose and object of my new and improved ironing board, consists in the table member supported upon pairs of leg supports, which said leg supports are in hinged relationship with the table member. Means are provided for hinged leg supports relative to the table member and for reciprocating one of said pairs of leg supports carrying a slide element journaled to one of the pairs of legs and slidable relative to the other.

A further object of my new and improved ironing board resides in the assembly that may be contracted into a minimum of space for shipment and delivery and that may be readily positioned for use without alteration.

A further object of my new and improved ironing board resides in providing means upon the top of the table structure to insulate the heated iron from the table during the use of the iron.

And still further objects of my new and improved ironing board reside in the simplified construction, of but few parts that become rigid when erected without the tightening of adjusting elements and that is of minimum weight and that will occupy a minimum of space when in use and when contracted for shipment and storage.

Still further objects of my new and improved ironing board reside in a board having a maximum of ironing space, and the board being reinforced laterally for preventing the warping, or buckling of the working surface. In ironing boards, the heated iron, when applied in its normal use, to the center, or central portion of the board has a tendency to warp, or curl the board. This generally causes the outer longitudinal edges of the board to turn, or curl upward. To prevent this tendency I reinforce the board laterally at one or more points to stiffen the same.

Still further objects of my new and improved structure reside in a board that is automatic in its erection. One that may be automatically extended from the folded position by the standing of the same on end and pressing downward upon the board portion of the same. This easily and quickly places the board in working position and condition. The board may be as easily and quickly

folded and placed out of working position, and made to occupy a minimum of space. Or again be placed in working condition by simply standing on one end and extending the same automatically into erected and usable position.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:—

Fig. 1 is a perspective, side elevation, of the assembled device, shown in readiness for use.

Fig. 2 is an inverted, plan, view of the device in contracted or folded position.

Fig. 3 is a side view of the device shown partially folded.

Fig. 4 is a fragmentary, cross section view, taken on line 4—4 of Fig. 1, looking in the direction indicated. This view is made to illustrate the shoe or sleeve in its relation with the primary and secondary leg supports with which it is associated.

Fig. 5 is a perspective, end, view, of the shoe or sleeve, shown removed from the leg elements and is made to illustrate the construction of the sleeve element and the journal bolt to which the same is adapted for engagement with the leg element.

Fig. 6 is a perspective, end, view of the shoe, or sleeve shown detached from the associated elements, the same being made to illustrate the projection formed on the exterior of the element that forms a recess on the exterior of the element into which the head of the fastening engages and thus forms a projection on the opposite side that acts as a separator for maintaining the associated leg elements in spaced relation with each other.

Like reference characters refer to like parts throughout the several views.

1 is the body or table element, having disposed its ends a bar 2, to which are attached

journal brackets 3 and 4. Running transversely of the brackets is a journal shaft 5. Primary leg supports 6 and 7 are hinged relative to the shaft 5, and a cross brace 6A secures the primary leg braces together. A second cross bar 8, is secured to the body element having journal brackets 9 and 10 secured thereto, and to the body member by any suitable fastening means. A second journal shaft 11, is journaled relative to the brackets 9 and 10 and secondary legs 12 and 13, are hinged relative to the journal shaft 11. The primary leg supports, each carry sliding shoes 14 and 15. Each of the shoes are journaled about supporting elements 16 and 17 that are fixedly secured to the primary legs, and slide relative to the secondary legs. A cross brace 18 secured to the primary legs acts as a stop or bar to the movement of the shoe, by the legs engaging the cross bar 18. The cross bar 19 maintains the secondary legs 12 and 13 in spaced relationship near their free extremities and imparts rigidity to the secondary leg braces. A metallic plate 20 is secured to the body member by any suitable fastening means and insulating material 21, as sheet asbestos, is placed between the metallic plate 20 and the body element upon which the flat iron is placed; the same being of sufficient thickness and insulating efficiently to prevent the burning of the body element by the heated flat iron when placed thereupon.

A depression 22 is formed within the legs 35 to permit of the cross brace being depressed therein when the ironing board is contracted for shipment and storage.

In detailed construction the sliding shoes or sleeves are as outlined in Fig. 5 and Fig. 6, wherein the sleeve element is preferably made of a sheet metal having a base 22A that is substantially the width of the leg adapted to slide relative thereto. Walls 23 and 24 are disposed at substantially right angles to the base and are substantially the depth of the thickness of the leg and rear walls 25 and 26 are disposed the terminal ends of the same. The edges 27 and 28 are in spaced relation with each other which facilitates manufacturing and at the same time facilitates the entry of the fastening bolt 16 therethrough. In order that the sleeves may be accurately made and a sliding fit be maintained between the sliding leg and the sleeve a depression 30 is formed within the sleeve into which the head 29 of the bolt may be made to engage. When the depression is formed within one side of the sheet stock from which the sleeve is made a projection 31 is formed upon the outside of the sleeve. The depression 31 acts as a spreader to maintain the leg elements in spaced relation with each other. The sleeve gives best results wherein sufficient tolerances are provided between the sleeve and the leg to per-

mit of a free sliding of the leg within the sleeve element.

To automatically raise or extend the board best results will be obtained if the board is held in an upright position; the free ends of the legs 6 and 7 as illustrated at 39 and 40 in Fig. 2, in contact with the floor. A slight downward pressure upon the board will cause a sliding of the sleeves 14 relative to the legs 12 and 13 until the board is erected to working position.

While the form of mechanism herein shown and described is admirably adapted to fulfill the objects primarily stated, it is to be understood that it is not intended to confine the invention to the one form of embodiment herein shown and described, it is susceptible of embodiment in various forms, all coming within the scope of the claims which follow:

What I claim is:—

1. An ironing board including folding legs for the same, the legs being fixedly hinged upon one end to the board member, sleeves carried by one pair of such legs within which the other pair of such legs are slidably, each of said sleeves constituting a single member formed of sheet material having a base or bed, upwardly turned side walls spaced apart, inwardly turned rear walls spaced from the bed and parallel thereto, the edges of the rear walls being spaced apart to provide an opening therebetween, and means for pivotally supporting such sleeve upon its associate carrier leg.

2. An ironing board including folding legs for the same, the legs being fixedly hinged upon one end to the board member, sleeves carried by one pair of such legs within which the other pair of such legs are slidably, each of said sleeves constituting a one piece member formed of sheet material having a base or bed, upwardly turned side walls spaced apart, inwardly turned rear walls spaced from the bed and parallel thereto, the edges of the rear walls being spaced apart to provide an opening therebetween, said bed having a centrally disposed depression, there being an aperture in such depression, and a bolt or pin passing through such aperture pivotally securing said sleeve to the leg by which it is carried.

3. An ironing board including folding legs for the same, the legs being fixedly hinged upon one end to the board members, sleeves carried by one pair of such legs within which the other pair of such legs are slidably, each of said sleeves constituting a one piece member formed of sheet material having a base or bed, upwardly turned side walls spaced apart, inwardly turned rear walls spaced from the bed and parallel thereto, the edges of the rear walls being spaced apart to provide an opening therebetween, and a bolt penetrating said bed and forming means for

pivotsly securing the aforesaid sleeve to the leg by which it is carried.

4. In a device of the class described, the combination of an ironing board, pairs of journal brackets spaced apart and disposed upon the under side of the ironing board, pairs of legs hingedly secured to the journal brackets, a cross brace fixedly disposed upon one pair of the legs and adapted for acting as a stop for the other pair of legs when the board is erected in ironing position, a second cross bar fixedly positioned upon the same pair of legs and a recess disposed in each of the other pair of legs and in registerable alignment with the cross bar when the board is folded and adapted to receive the cross bar therein, a pair of sleeves slidably disposed upon one pair of the legs and pivotally disposed upon a journal fastening that is fixedly disposed upon the other pair of legs.
